UNITED STATES PATENT OFFICE

JOHN MAGILL, OF BEVERLY, MASSACHUSETTS, ASSIGNOR TO THE TAYLOR ATKINS PAPER COMPANY, OF BURNSIDE, CONNECTICUT, A CORPORATION OF CONNECTICUT

MACHINE FOR BANDING SHEETS

Application filed May 27, 1931. Serial No. 540,221.

This invention relates to a machine which is designed to wrap bands, preferably paper although they may be of other material, around a number of superposed sheets or 5 cards of paper or other material, for packaging the sheets or cards.

The object of the invention is to provide a relatively simple, inexpensive and rapidly operating machine which will receive and 10 feed the quantities of loose sheets or cards to be packaged over a magazine containing the bands, and will apply adhesive to and fold the bands about the sheets or cards so as to hold the sheets or cards in the desired pack- 15 age form.

The machine illustrated as embodying the invention was primarily designed for packaging sheets of paper with paper bands, and will be so described, although the invention 20 is not limited to the specific materials of the sheets or bands to be packaged. In this machine there are means for receiving and locating the sheets to be banded and delivering them to means which conveys them over 25 the bands that are stacked in a magazine which has means for lifting the bands so that the uppermost is always at the proper level to be folded around the sheets. When a bundle of sheets is over the bands the ends 30 of the top band are separated from the band underneath and folded over the sheets, one end of the band as it is folded being engaged with means which applies adhesive so that the ends of the band wrapped around 35 the sheets will be fastened together and hold the sheets. Means are also provided for causing the machine to stop should sheets fail to feed over the bands.

In the accompanying drawings Fig. 1 is a 40 vertical section showing the means for receiving and conveying the sheets over the bands. Fig. 2 is a plan of the sheet feeding mechanism. Fig. 3 is an end view of the sheet locating and feeding mechanism. Fig. 45 4 shows a plan of the means for folding the ends of the bands about the sheets. Fig. 5 is a front elevation of the band folding means. Fig. 6 is a side elevation of the band folding means and gumming means. Fig. 7 is a view 50 of the band folding mechanisms in the posi-

tions occupied when an end of a band being folded is engaging the adhesive applying means. Fig. 8 is a diagram illustrating the band folders as they start. Fig. 9 is a diagram showing the folders a little further 55 advanced. Fig. 10 is a diagram showing one end of a band completely folded and the other end engaging the gumming means. Fig. 11 shows the position of the folders with a band completely folded and adhered. 60 Fig. 12 is a view showing the means for separating the ends of the top band from the band underneath so that the folding fingers may pass under the top band.

A number of superposed sheets of paper 65 1 to be banded are placed on a pair of swinging arms 2 that are pivoted on a shaft 3 at the rear of the machine, Fig. 1. The arms have gauge fingers 4 for ensuring the correct location of the sheets on the arms. One of the 70 arms has a roll 5 that is engaged by a cam 6 fixed on a shaft 7 which extends across the frame.

Between the sheet receiving arms is an endless chain 8 that passes around a sprocket wheel 9 fastened on the shaft 7, and a driving sprocket wheel 10 fastened on a shaft 11. It is preferred to have the distance from center to center of the sprocket wheels exactly equal to the length of the pitch circle of the driving 75 sprocket, for the reason hereinafter mentioned. This chain at the required distances apart has push fingers 12. The cam 6 at the proper time raises the arms for receiving the sheets and then allows them to swing down 80 and deposit the sheets over the chain with their edges resting on guide rails 13 which are adjustably fastened to the frame, in such position that when a finger on the chain comes along it pushes the sheets along the rails to a 85 locality over the bands 14, Figs. 1, 2.

The shaft 11 with the sprocket wheel 10, is driven through the worm wheel 15 and a clutch 16, the clutch members being normally kept in engagement by a spring 17. Pivoted 90 at one side of the machine is a lever 18 that at its upper end has an arm 19 which carries a roll 20 over the path of the sheets conveyed by the chain. The sliding member of the clutch has a cam 21 and a cam groove 22. 100

The lever 18 at its lower end has a shoe 23 engaged by the cam 21, and it has a roll 24 which is adapted to enter the cam groove 22. The high part of the cam 21 lifts the roll 20 and the low part allows the roll 20 to drop at each rotation of the shaft 11. If paper is being fed the roll 20 engages it and retains the lever 18 so that the roll 24 will not enter the cam groove 22, but if no paper is being carried by the chain the roll 20 drops sufficiently for the roll 24 to enter the cam groove 22 and then this cam causes the withdrawal of the movable member of the clutch so that the machine will stop. If the distance from center to center of the sprocket wheels is equal to the pitch circle of the driving sprocket, as above suggested, the feed chain moves that distance at each complete cycle of the machine, making it impossible, in combination with the stop mechanism, to cause waste of bands by allowing a second cycle of the motion if no paper is fed in.

The bands 14 are cut to suitable width and length and are piled in a magazine 25 at the front of the machine. The bottom 26 of the magazine is lifted by springs 27 on rods 28 that are connected with levers 29 which are fastened to a shaft 30 that extends across the frame. Connected with this shaft is a treadle 31, Fig. 6. When the treadle is pressed down the springs are compressed and the bottom of the magazine is lowered so that the bands may be placed in the magazine. The springs normally lift the magazine bottom so that the uppermost band is just beneath the sheets of paper which are fed over the magazine by the conveyer chain. Small spring fingers 32 are arranged at the top of the magazine near the ends to prevent the bands from being lifted too high, Fig. 2.

In the machine illustrated there are four fingers 33 carried by the upper ends of angle levers 34 in such manner that they will bear down upon the top band on opposite sides near the ends. The front and back angle levers are connected together, Fig. 6, and the rear pair have rolls 35 that are engaged by cams 36 on the drive shaft. At the proper time these cams swing these fingers transversely across the top band and by friction cause its ends to bow up, as shown in Fig. 12.

Movable toward each other from side to side over the band magazine are slides 37, 38, which carry folder blades 39, 40. A cord 41 is connected with the slide 37 and passed around rolls 42, 43, the latter of which is mounted on the upper end of a lever 44 pivoted on a stud 45 that projects from one side of the rear frame. This lever has a roll 46 that is engaged by a cam 47 on the drive shaft. Connected to the slide 38 is a cord 48 which passes around rolls 49, 50, the latter of which is mounted on the upper end of the lever 51 which is also pivoted on the stud 45. This lever has a roll 52 that is engaged by a cam 53

on the drive shaft. These cams 47, 53 are so timed that the levers through the cords first move the slide 38 with the folder blade 40 in under one uplifted end of the uppermost band, as shown in Fig. 8. As this blade continues to move in the blade 39 on the slide 37 enters beneath the other lifted end of the band, as shown in Fig. 9. The continued movement of the blade 40 completes the folding of one end of the band down upon the paper, and the continued movement of the blade 39 causes the other end of the band to fold over, and while being folded to engage with a tube 54 which leads from a reservoir 55, Fig. 6, containing adhesive, so that a small coating of adhesive is applied to the under side of this latter end of the band as it is folded over, as indicated in Fig. 10. Further movement of the blade 39 completes the folding of the gummed end of the band and presses it down on the other end, causing the ends to adhere. The adhesive reservoir is mounted on a support 61 that extends upward from the frame. The slide 37 with the blade 39 is retracted by the weight 57 fastened to the end 70 of the cord 58, and the slide 38 with the blade 40 is retracted by the weight 59 attached to the cord 60. These weights hold the operating levers against the actuating cams.

The mechanism described feeds the sheets 95 and folds the bands about them very rapidly and accurately, and should there be a failure of feed of sheets the machine will stop without waste of bands.

The invention claimed is:

1. A machine for banding sheets which comprises a magazine for receiving bands, means for receiving and conveying the sheets over said magazine, means for raising the ends of the top band from the band below, means for entering beneath said raised ends of the top band and folding the ends over on the sheets, and means for applying gum to one of said band ends as it is folded over and down upon the other end. 100

2. A machine for banding sheets which comprises a magazine for receiving bands, means for raising the bottom of said magazine so that the uppermost band will always be at the same level, means for receiving and conveying sheets over said magazine, means for raising the ends of the top band from the band below, means for entering beneath said raised ends of the top band and folding the ends over on the sheets, and means for applying gum to one of said band ends as it is folded over and down upon the other end. 110

3. A machine for banding sheets which comprises a magazine for receiving bands, means for receiving and conveying sheets over said magazine, means for raising the ends of the top band from the band below, means for entering beneath said raised ends of the top band and folding the ends over on the sheets, means for applying gum to one of said band 125

- ends as it is folded over and down upon the other end, a driving mechanism which includes a clutch, and means for releasing said clutch if no sheets are conveyed to a position 5 over the bands.
4. A machine for banding sheets which comprises a magazine for receiving bands, means for conveying sheets over said magazine, means for receiving sheets and placing them in the path of said conveying means, means for raising the ends of the top band from the band below, means for entering beneath said raised ends of the top band and folding the ends over on the sheets, and 10 means for applying gum to one of said band ends as it is folded over and down upon the other end.
5. A machine for banding sheets which comprises a magazine for receiving bands, an 20 endless chain for conveying sheets over said magazine, oscillatory fingers for receiving the sheets and depositing them in the path of said chain, means for raising the ends of the top band from the band below, means for 25 entering beneath said raised ends of the top band and folding the ends over on the sheets, and means for applying gum to one of said band ends as it is folded over and down upon the other end.
6. A machine for banding sheets which comprises a magazine for receiving paper bands, an endless conveyer for receiving and carrying sheets over said magazine, means for raising the ends of the top band from the 35 band below, means for entering beneath said raised ends of the top band and folding the ends over on the sheets, means for applying gum to one of said band ends as it is folded over and down upon the other end, a driving 40 mechanism which includes a clutch, an arm adapted to oscillate across the path of the sheets being carried by the conveyer, and means connected with said arm and adapted to release said clutch wherever said arm swings below the path of the sheets.
7. A machine for banding sheets which comprises a magazine for receiving bands, means for receiving and conveying sheets over said magazine, fingers engaging opposite edges near both ends of the top band for separating the ends from the band below, means for entering beneath said raised ends of the top band and folding the ends over on the sheets, and means for applying gum to one of said band ends as it is folded over and down upon the other end.
8. A machine for banding sheets which comprises a magazine for receiving bands, means for receiving and conveying sheets over said magazine, means for raising the ends of the top band from the band below, a slide movable toward and from each end of the bands, folding blades carried by said slides and adapted to enter beneath said raised ends of the top band and fold them 50 over on the sheets, and means for applying gum to one of said band ends as it is folded over and down upon the other end.
9. A machine for banding sheets which comprises a magazine for receiving bands, means for receiving and conveying sheets over said magazine, means for raising the ends of the top band from the band below, a slide movable toward and from each end of the bands, cords, levers and cams for moving said slides toward each other and cords and weights for moving said slides away from each other, blades carried by said slides and adapted to enter beneath said raised ends of the top band and fold the ends over on the sheets, and means for applying gum to one of said band ends as it is folded over and down upon the other end.
10. A machine for banding sheets which comprises a magazine for receiving bands, an endless chain for receiving and carrying sheets over said magazine, means for raising the ends of the top band from the band below, slides movable back and forth transversely to the path of said chain, blades carried by said slides for entering beneath said raised ends of the top band and folding the ends over on the sheets, and means for applying gum to one of said band ends as it is folded over and down upon the other end.
11. A machine for banding sheets which comprises a magazine for receiving bands, means for receiving and conveying sheets over said magazine, fingers engaging opposite edges near both ends of the top band for separating the ends from the band below, blades for entering beneath said raised ends of the top band and folding the ends over on the sheets, and gumming means extending into the path of one end of the top band as it is folded over and down upon the other end.
12. A machine for banding sheets which comprises a magazine having a vertically movable bottom for supporting bands, springs normally tending to lift said bottom, a treadle connected to the magazine bottom and adapted to lower the same against the tension of the springs, means for receiving and conveying the sheets over said magazine, means for raising the ends of the top band from the band below, means for entering beneath said raised ends of the top band and folding the ends over on the sheets, and means for applying gum to one of said band ends as it is folded over and down upon the other end.
13. A machine for banding sheets which comprises a magazine for receiving bands, an endless chain passing around sprocket wheels for conveying sheets over said magazine, the distance between the centers of said sprocket wheels being equal to the pitch diameter of said wheels, means for receiving sheets and placing them in the path of said chain means,

means for raising the ends of the top band from the band below, means for entering beneath said raised ends of the top band and folding the ends over on the sheets, and means 5 for applying gum to one of said band ends as it is folded over and down upon the other end.

14. A machine for banding sheets which comprises a magazine for receiving bands, 10 means for receiving and conveying sheets over said magazine, means engaging opposite edges near both ends of the top band for separating said band ends from the band below, blades for entering beneath said raised ends 15 of the top band and first folding one end over on the sheets and then folding the other end over the sheets and pressing it down on the end first folded, and gumming means extending into the path of the end of the top band last folded over.

15. A machine for banding sheets which comprises a magazine for receiving paper bands, an endless conveyer for receiving and carrying sheets over said magazine, means 25 for raising the ends of the top band from the band below, means for entering beneath said raised ends of the top band and folding the ends over on the sheets, means for applying gum to one of said band ends as it 30 is folded over and down upon the other end, a driving mechanism, an arm adapted to move into the path of the sheets being carried by the conveyer, and mechanism connecting said arm and driving mechanism and adapted to disconnect the driving mechanism wherever said arm swings below the path of 35 the sheets.
